DRAWING TEMPLATE

Arthur L. Thomas, 1665 Glenway Lane,
Huntington, W. Va.

Filed July 16, 1963, Ser. No. 75,837

Term of patent 14 years

(Cl. D52—6)

The characteristic feature of the disclosed design for a template resides in the arrangement of the symbols therein.

I claim:

The ornamental design for a drawing template, as shown and described.
